UNITED STATES PATENT OFFICE.

GEORGE THOMAS PRITCHARD, OF NORFOLK, VIRGINIA.

TAG-ADDRESSING MACHINE.

1,170,932.

Specification of Letters Patent.

Patented Feb. 8, 1916.

Application filed January 26, 1914. Serial No. 814,437.

To all whom it may concern:

Be it known that I, GEORGE T. PRITCHARD, a citizen of the United States, residing at Norfolk, in the county of Norfolk and State 5 of Virginia, have invented a new and useful Tag-Addressing Machine, of which the following is a specification.

This invention has reference to improvements in tag addressing machines, and its 10 object is to provide a machine with which shipping or other tags or like articles may be expeditiously addressed in such numbers as may be desired.

In accordance with the present invention 15 there is provided a reservoir or container for tags, and in position to reciprocate across the mouth or discharge end of the reservoir is a slidable member constructed to remove the tags one at a time from the reservoir and 20 when a tag is removed it is positioned in the path of a printing mechanism, by means of which the desired impression may be imparted to the tag, and then on the release of the actuating mechanism the slidable member 25 or bed is returned to its first position ready on the next actuation to remove another tag for printing. On each return of the bed to its initial position the printed tag is discharged from the bed so as to be out of 30 the way of the next tag in order. To facilitate the addressing of the tags in desired numbers, there is a register associated with the mechanism to be actuated at each operation of the printing mechanism, so that the 35 operator knowing the number of tags to be printed with a certain address or other matter has but to add such number to the number displayed in the register and then operate the machine until the number is displayed, it being understood, of course, that a supply of tags is on hand in the reservoir.

The invention will be best understood from a consideration of the following detailed description, taken in connection with 45 the accompanying drawings, forming a part of this specification, with the further understanding that while the drawings show a practical form of the invention, the latter is not confined to any strict conformity with 50 the showing of the drawings, but may be changed and modified so long as such

changes and modifications mark no material departure from the salient features of the invention.

In the drawings:—Figure 1 is a perspective view of the machine in the position assumed by the parts as a tag is being imprinted. Fig. 2 is a longitudinal vertical central section of the machine with the parts in the normal position. Fig. 3 is a view 60 similar to Fig. 2 but showing the parts in the position indicated in Fig. 1. Fig. 4 is a front elevation of the machine with some parts in section. Fig. 5 is a perspective view of the slidable plate or bed. Fig. 6 is 65 a perspective view of the operating arm or yoke lever. Fig. 7 is a perspective view of one of the motion multiplying arms between the operating arm and the bed. Fig. 8 is a section on the line 8—8 of Fig. 2 drawn on a 70 larger scale and omitting distant parts. Fig. 9 is a perspective view of one of the spring fingers used in the machine.

Referring to the drawings, there is shown a casing 1 including a bottom member 2, 75 sides 3 and a back 4, the latter being shown as slanting forwardly, as indicated at 5, at the upper portion. The casing 1 may be mounted on feet 6 usually of some sound deadening material, such as rubber or felt. 80 On the inner wall of each side at an appropriate distance above the bottom 2 is a longitudinal channel 7, the channels facing each other and so related as to receive the edge portions of a plate 8, which, as will 85 hereinafter appear, is designed to carry tags and serve as a bed for supporting the tags during the imprinting operation. A portion of one end of the plate 8 is cut away leaving spaced side members 9 to the under 90 side of each of which there is secured a strip 10 extending toward the other side member 9 to form a ledge for the reception of a filler plate 11 which may be of less thickness than the plate 8, so that when supported upon the ledges 10 the surface of the plate 11 is slightly depressed with respect to the surface of the plate 8. When the plate 11 is secured to the ledges 10 the rear edge of the cut away portion of the plate 8 100 forms a shoulder 12 of an extent equal to the space between the side extensions 9 and

of a depth equal to the depression of the upper surface of the plate 8, this depression being regulated by the thickness of the plate 11 with respect to the thickness of the plate 5 8 and may be reduced by placing shims upon the ledges 10, this being a customarily employed form of adjusting means. The depth of the shoulder 12^a may coincide with the thickness of a tag or may be less than 10 such thickness, but should not be greater than such thickness. Certain portions of the surface of the plate 11 are grooved or still further depressed than other portions to receive strips 12 and 13 of some frictional 15 material, such as soft rubber or the like, the strips 12 being adjacent to the extensions 9 and the strip 13 being about midway of the length of the plate 11 as measured cross-wise of the bed 8, and the strip 13 may be 20 considerably wider than either of the strips 12. The side edges of the strip 13 are spaced from the corresponding edges of the strips 12 leaving portions 14, 15 of the filler plate 11 exposed and on approximately the level 25 of the adjacent friction strips, the portion 15 being somewhat lower than the portion 14, but adjacent to the strip 13 being of the same height, such portion being indicated at 16. The plate 8 adjacent to the shoulder 30 12^a is provided with a series of notches 17, 18, respectively, having inclined bottoms so that the notches gradually deepen toward and attain their full depth at about the shoulder 12^a. These notches lead to the portions 14, 15 and 16 of the filler plate 11 for 35 a purpose which will presently appear.

At opposite sides of the bed plate 8 near the margins the plate is pierced by elongated slots 19, while near that end of the plate 40 which may be termed the rear end angle brackets 20 are made fast to the plate by screws 21 or other arrangements may be employed, the purpose of the brackets 20 being to serve as stops.

45 The sides 3 of the frame or casing 1 are carried to an appropriate height and terminate in laterally thickened portions 22 designed to receive angle ears 23 on opposite ends of a reservoir 24, which latter may be 50 of general rectangular cross section and of an area and shape to receive a pile of tags 25, these tags being usually of the type known as shipping tags and are customarily made of a rectangular sheet of heavy Manila paper or cardboard with one end provided with an eye and there reinforced, as is customary, such reinforcement about the eye correspondingly thickening the tags, and for this reason the portion 15 of greater 55 depression is provided in the filler plate 11 to allow for such additional thickness at the corresponding end of the tag, it being understood that when the tags are placed in a reservoir their thickened ends always occupy

the same relative position in the reservoir, 65 and in the particular showing of the drawings this is the left hand end of the reservoir as viewed in Fig. 1. The reservoir is ordinarily open top and bottom so far as the reservoir itself is concerned, but is so situated 70 with reference to the bed plate 8 that the latter constitutes a bottom member for the reservoir. Furthermore, the reservoir is so situated in the casing 1 that when the plate 8 is moved in the casing until its ear edge 75 abuts against a buffer 26 on the inner face of the rear wall 4, the filler plate 11 then underlies the reservoir preventing any tags 25 which may be in the reservoir from escaping, while the shoulder 12 is slightly to the 80 rear of the inner back wall of the reservoir. The front wall of the reservoir is cut away at the bottom for the full width of the interior of the reservoir, as indicated at 27, and this cut away portion is of the least 85 height at the ends and of greater height where coinciding with the parts 14, 15 and 16 of the plate 11, as indicated at 28. The intermediate portion of the cut away part 27 is of still greater height, as indicated at 29, to provide a sight opening whereby the observer may ascertain when the supply of tags within the reservoir is diminishing to such an extent as to demand replenishment.

Made fast to the front wall of the reservoir 95 are fingers 30 each near the outer end of the higher portion 28 of the cut away part of said front wall and also made fast to the front face of the reservoir 24 are other fingers 31 adjacent to the sight opening 29. These fingers are so arranged that the fingers 30 are in line with the notches 17 and the fingers 31 are in line with the notches 18. All the fingers may be made fast to the reservoir by screws 32 or in any 100 other suitable manner.

One of the fingers 30 is shown separately in Fig. 9, the finger being secured at an intermediate point of its length to the reservoir 24, one end 33 of the finger being in 110 the form of a return bend terminating in an upturned angle extension 34 so disposed as to underlie the front wall of the reservoir 24 without of necessity entering the reservoir but resting lightly upon the portion of the 115 filler plate 11 underlying the finger, and when, as will hereinafter appear, the main body of the plate 8 is moved into underlying relation to the reservoir, the return end 33 of the finger 30 readily yields to the 120 increasing thickness of the plate. The other end 35 of the finger 30 is forwardly bent in a direction away from the reservoir 24 and downwardly bent toward the path of movement of the filler plate and terminates in a 125 prolongation 36 which, as will hereinafter appear, may be brought into contact with the tag resting upon the filler plate.

The fingers 31 have each an angle extension 37 projecting away forwardly from the front face of the reservoir 24 and terminating in an upturned end 38. These fingers 31 are located in line with the notches 18 so as to ride upon the portions 14 and 16 of the filler plate 11.

The reservoir 24 is of less length cross-wise of the casing than the distance between 10 the inner faces of the side members to leave room for certain mechanism to be described. Near the upper portion of each side member there is formed a boss 39 projecting inwardly from the inner wall of the side member, and such boss receives a screw 40 constituting a pivot support for the upper end of a depending rocker-arm 41 shown separately in Fig. 7. This arm is widened at the pivoted end and there is provided with 15 a longitudinal slot 42, while the end of the arm remote from the pivoted end is recessed, as shown at 43, thereby forming a longitudinal extension 44 of less width than the arm 41 adjacent to the recess 43. One of the two 20 arms 41 has a link 45 connected to it near its pivoted end, and this link is carried to a rock arm 46 on a counter or registering mechanism 47 carried by a bracket support 25 made fast to the corresponding side of 30 the casing.

Straddling the reservoir are the arms of a yoke lever 49 having the yoke portion provided with a projecting finger piece 50 by means of which the yoke lever may be manipulated. The leg members of the yoke lever terminate in perforated ears 51 in line with the leg members, and adjacent to these ears each leg member has an angle extension 52 provided at the free end with a passage 40 53 through which extends a pivot screw 54 threaded into the adjacent side member 3, so that the yoke lever may rock upon the screws 54 fastening it to the inner faces of the two side members 3. When the angle 45 extensions 52 join the legs of the yoke lever the latter has aligned passages 55 into which are threaded screws 56 each carrying an anti-friction roller 57 lodged in the slot 42 of the corresponding arm 41. Connected to 50 each ear 51 is one end of a coiled spring 58, the other end of which is made fast to a threaded rod 59 extended through a boss 60 on the angle portion 5 of the back 4 of the casing, and this rod is threaded for the 55 reception of a thumb nut 61 by means of which the rod 59 is held in the boss 60 in adjusted positions, whereby the tension of the respective springs 58 may be regulated.

The yoke portion of the lever 49 on opposite sides of the manipulating member 50 is provided with lugs 62 to which there is secured a plate 63 by screws 64, this plate being elongated transversely of the length of the lever 49, and the lugs 52 are so

shaped that the plate 63 is set at an appropriate angle to the general plane of the lever 49. The plate 63 is designed to receive and retain a box 65 which may be of generally rectangular shape and opposite ends of this box are inturned, as indicated at 66, to embrace opposite edges of the plate 63, so that the box may slide on to or be removed from the plate, the front 67 of the box serving as a stop limiting the movement of the box on to the plate, while a spring latch finger 68 carried by the plate 63 serves to hold the box to the plate against accidental removal.

What constitutes the bottom of the box 65 is in the form of an inturned ledge 69 of short extent, leaving the main portion of 80 the bottom of the box open. This ledge receives and retains a pad 70 of sufficient thickness at the open bottom of the box to project therethrough so that the outer end of the pad is beyond the bottom of the box. 85 The pad is of such thickness within the box as to leave considerable space which is occupied by a pan 71 having a perforated bottom 72, this pan being designed to receive ink which finds its way through the 90 perforations to the pad, and the box not only holds the pad in place but serves to distribute the ink therethrough. The pan 71 is of such length that it may be removed through the open top of the box when the 95 box is taken from the plate 63 by sliding the pan to one end of the box, whereupon the other end of the pan may be lifted without interference from the inturned end or flange 66 of the box. The pad is designed to receive 100 a stencil or other appropriate sheet 73 held at the edges against the flange 69 by a frame 74 having end ears 75 engaging spring members 76 fast on the ends of the box 65. Of course, it will be understood 105 that any other suitable arrangement may be provided for holding the stencil members.

Those ends of the side arms 41 having the extensions 44 project through the slots 19 in the plate 8 and the length of the arms 41 is such that at no time will these arms escape from the plate 8. In order to limit the movement of the plate 8 away from the buffer 26 toward the front of the casing, stop lugs or other suitable stop members 77 115 are formed on the inner walls of the sides 3 in the path of the brackets 20.

Let it be assumed that a suitable number of tags 25 is lodged in the reservoir 24 and that it is desired to imprint a certain address or other matter upon a certain number of tags. The address containing sheet 73 which may be made of suitable material customarily employed in connection with printing machines of the general character of the 120 present invention is secured over the pad 70 so that ink will pass through the sheet 73 by way of stencil or other formation of the 125

sheet, such stenciling or other formation being accomplished by a typewriter or by a pencil or other marking tool or in any way customarily practised. The ink will 5 not spontaneously flow through the stencil sheet but may be forced therethrough by pressure. Now, if the structure be assumed to be in the position shown in Fig. 2 the operator depresses the lever 49 by a manipulation of the finger piece 50, this resulting in a rocking of the lever upon the pivot screws 54 and as the arms 52 traversed by these screws are at an angle to the main body of the lever the angle connection of 10 the arms and lever moves forwardly in an arc about the screws 54 and the printing member represented by the box 65 is carried in an arc toward the path of the plate 8, this plate being impelled along the grooves 15 20 by the coaction of the lever 49 and rock arms 41 connected by screws 56. The free or lower ends of the arms 41 being lodged in the slots 19 cause a forward movement of the plate 8 as the arms rock from a rearward 25 position toward the front, and this movement continues because of the timing and proportioning of the parts until the stop members 20 engage the stops 77, whereupon the movement of the plate 8 is 30 arrested, but at this point the shoulders formed by the recesses 43 escape from engagement with the plate 8, so that the latter is no longer impelled but comes to rest while the arms 41 may have a further extent 35 of movement.

When the parts are in their normal position, as shown in Fig. 2, the lower one of the stack of tags 25 rests upon the filler plate 11 in engagement with the friction surfaces 12 40 and 13 and the rear edge of the lowermost tag in engagement with the shoulder 12^a. As the plate 8 moves forwardly the lowermost tag is carried with it, and while the return portion 33 and 34 of the fingers 30 45 may at this time be in engagement with the lowermost tag the latter is thin and the junction of the upward extension or lip of each finger 33 is rounded, so that the tag readily passes beneath the finger, but the next tag 50 above cannot move from the reservoir because it is engaged by the lip 34 and the friction between the lowermost tag and the next above it is insufficient to overcome the resistance thus offered. As the plate 8 moves 55 forwardly the lowermost tag is carried with it, slipping under the extension 37 of the finger 31 until it passes the upturned lips 38 at the ends of these fingers 31, but is still underneath the extremities 36 of the finger 60 extension 35. The movement of the plate 8 continues until arrested by the stop devices, but the yoke lever 49 has not yet reached the limit of its downward travel toward the bed plate, this extra movement being permitted

by the recesses 43 in the arms 41, and this 65 lost motion permits the final movement of the stencil sheet 73 into printing engagement with the tag carried by the filler plate 11 constituting an extension of the bed plate 8. The rear edge of the printing member 70 engages the terminal portions 36 of the extensions 35 of the fingers 33 and the tag is effectively gripped during the printing operation against accidental movement which might result in a blur in the printing. Now, 75 the operator releases the pressure upon the finger piece 50, whereupon the springs 58 return the lever 49 to its first position and reverses the rocking movements of the arms 41, and thereby causing a return of the 80 plate 8 to its first position. This movement first permits the lifting of the printing member from the tag, and then the engagement of the prolongations 44 of the arms 41 with the rear walls of the slots 19, thus causing 85 a return or reverse movement of the plate 8 toward the first position. As the tag is carried rearwardly with the plate it comes into engagement with the upturned extremities 38 of the finger ends 37 and the tag is 90 thereby discharged from the bed plate falling into the portion of the casing beneath it. The next tag in order in the reservoir is now in position to be projected and printed and the operation may be repeated as many 95 times and as rapidly as needed until the desired number of tags have been printed.

It is only necessary to maintain a supply of tags in the reservoir and to observe from time to time the counter or indicator mechanism 47 in order to imprint the desired number of tags, changing the stencil sheet as often as may be desired.

The construction of the bed plate in two parts permits the adjustment of the part 105 designed to directly receive the tags in an up and down direction to allow for differences in thickness of the tags. The ink employed in printing is of a more or less sticky nature, and consequently there is a tendency 110 of the tag sticking to the printing surface, but this is overcome by the finger extensions 35 which strip the tag after printing from the printing pad should there be any tendency to stick. Moreover, the spring fingers, 115 and especially the portions 33 and 37 thereof hold the tag steady and firm, while it is being drawn by the sliding plate from the reservoir. Since that portion of the filler plate designed to receive the eye end of the 120 tag is somewhat lower than the rest of the plate, the tag will lie flat upon the bed plate, so that the printing mechanism may be brought down firmly upon the tag. The engagement of the tag with the shoulder 12^a 125 and with the superior friction surfaces provided by the rubber strips insures the bringing out of a tag upon the plate each time the

- plate is moved forward. When the number of tags desired have been printed from one stencil sheet, another is very readily substituted by a removal of the holding frame 74.
- 5 By bringing the bed plate to a full and positive stop at the end of its forward travel overriding of the plate is prevented, and as at this time the printing device is not yet in contact with the tag the stoppage of the 10 plate insures an automatic steady positioning of the tag during the printing operation.

Since the printing device moves against the tag from above, the tags are placed in the reservoir face upwardly, and since it is 15 convenient to have the printing as produced properly readable by the operator, the high ends of the tags are placed in the reservoir so that they occupy the end thereof toward the left hand side of the operator.

20 Because of the reinforcements about the eyes of the tags and the greater depression of the part 15 of the filler plate to accommodate such reinforcement, and, furthermore, because of the circumscribed area of 25 such reinforcement, the weight of the tags above the lowermost one is liable to slightly bend down the adjacent portions of the next tag above the lowermost one sufficiently to cause it to be engaged by the shoulder 12^a 30 where deepened by the more depressed portion 15, were it not for the presence of a supplementary layer or thickening of the friction surface 12 adjacent to the depressed portion 15, this thickening being about on 35 the level with the level of the portion 16, and is indicated at 16^a in Fig. 5. The presence of the portion 16^a maintains the corresponding portions of the lowermost and next higher tag in proper relation to the shoulder 12^a, so that on the removal of the lowermost 40 tag the shoulder 12^a does not engage the next higher tag.

What is claimed is:—

1. In a tag printing machine, a reservoir or receptacle for tags, reciprocable tag holding means movable with relation to the receptacle to carry one tag at a time therefrom into printing position, a printing device, means for moving the printing device into and out of engagement with the projected tag, and connections from the means for moving the printing device to the tag holding means movable out of propelling engagement therewith on the attainment of 5 the tag holding means to printing position, whereby the printing mechanism has a range of movement to effect the printing during a period of rest of the tag holding means.
- 10 2. In a tag printing machine, a reservoir or receptacle for tags, a reciprocatory bed plate movable across the bottom of the reservoir and constructed to project one tag at a time from the reservoir into position

to be printed, a rockable operating member 65 for the bed plate, a printing device, and rockable operating means for the printing device connected to the first-named rockable means for actuating the same and said first-named operating means having a connection 70 with the bed plate for movement out of propelling relation thereto after the bed plate has come to rest and before the second-named operating means has reached the limit of its movement.

75 3. In a tag printing machine, a reservoir or receptacle for tags, a reciprocatory bed plate movable across the bottom of the reservoir and provided with means for engaging and projecting one tag at a time from the 80 reservoir, means for limiting the movement of the bed plate in a direction to project the tag, a rockable operating member, a printing device carried by the operating member and movable thereby toward and from the 85 bed plate when the latter is in the projected position, and rockable connections between the rockable operating member and the bed plate having connections with the latter movable out of operative engagement there- 90 with when the bed plate reaches the limit of its movement and before the printing device reaches the projected tag to print the latter.

4. In a tag addressing machine, a receptacle or reservoir, a bed plate movable transversely of the lower end of the reservoir and provided with a tag engaging portion, tag holding and arresting members carried by the reservoir in the path of tags within 100 the reservoir and in the path of return movement of a projected tag, an operating member, an imprinting device carried by the operating member, and connections between the operating member and the bed plate for 105 causing reciprocations of the latter.

5. In a tag addressing machine, a reservoir or receptacle, a reciprocatory bed plate movable beneath the reservoir and forming a support for tags lodged within the reservoir, said bed plate having means for engaging and projecting the tag resting upon the bed plate when the latter is in the retracted position, an operating member, a printing device carried by the operating 110 member and movable therewith into and out of engagement with a projected tag, and lost motion operating connections between the operating member and the bed plate comprising rock arms projecting through 115 the bed plate and connected to the operating member, each rock arm having an extension of less width in the direction of travel than the arm and the bed plate being provided with passages for the rock arms each of a 120 length to receive the wider portion of the arm.

6. In a tag addressing machine, a casing,

- a bed plate mounted for reciprocation in the casing, a reservoir for tags mounted above the bed plate with the latter constituting the bottom member of the reservoir,
- 5 a rock lever having angle extensions and pivotally mounted by said angle extensions, a printing device carried by the rock lever and movable thereby toward and from the path of the bed plate, the latter being provided with elongated slots on opposite sides, and rock arms each pivotally carried at one end by the casing and at the other end projecting through a respective slot in the bed plate and also operatively connected to the 10 rock lever, that end of each arm projecting through the bed plate having an extension of less width than the width of the arm in the direction of its travel where projecting through the bed plate.
- 15 7. In a tag addressing machine, a casing, a bed plate mounted for reciprocation in the casing, a reservoir for tags mounted above the bed plate with the latter constituting the bottom member of the reservoir,
- 20 25 a rock lever having angle extensions and pivotally mounted by said angle extensions, a printing device carried by the rock lever and movable thereby toward and from the path of the bed plate, the latter being provided with elongated slots on opposite sides, and rock arms each pivotally carried at one end by the casing and at the other end projecting through a respective slot in the bed plate and also operatively connected to the 25 rock lever, that end of each arm projecting through the bed plate having an extension of less width than the width of the arm in the direction of its travel where projecting through the bed plate, said bed plate and 30 casing having coacting stop members for arresting the travel of the bed plate in one direction before completion of the travel of the rock lever, and the rock arms being related to the bed plate to have their broader 35 portions escape therefrom when the forward travel of the bed plate is arrested.
- 35 8. In a tag addressing machine, a suitable casing, a bed plate mounted for reciprocation in the casing, a reservoir mounted in the casing in overriding relation to the bed plate and the latter constituting the bottom of the reservoir, a yoke lever having angle extensions and pivotally mounted by said extensions in the casing in straddling relation to the reservoir, rock arms pivotally mounted in the casing on opposite sides of the reservoir and each projecting through a corresponding portion of the bed plate, the latter having elongated slots for the purpose, and the end of each arm where projecting through the corresponding slot in the bed plate having an extension of less width than the arm, pivotal connections between the rock lever and the rock arms, and

a printing device carried by the rock lever 65 in position to engage a tag carried by the bed plate when in the projected position.

9. In a tag addressing machine, a suitable casing, a bed plate mounted for reciprocation in the casing, a reservoir mounted in the casing in overriding relation to the bed plate and the latter constituting the bottom of the reservoir, a yoke lever having angle extensions and pivotally mounted by said extensions in the casing in straddling relation to the reservoir, rock arms pivotally mounted in the casing on opposite sides of the reservoir and each projecting through a corresponding portion of the bed plate, the latter having elongated slots for the purpose, 80 and the end of each arm where projecting through the corresponding slot in the bed plate having an extension of less width than the arm, pivotal connections between the rock lever and the rock arms, and a printing 85 device carried by the rock lever in position to engage a tag carried by the bed plate when in the projected position, the machine being provided with spring connections between the casing and the operating lever for 90 returning the parts to one limit of movement of the bed plate.

10. In a tag addressing machine, the combination with a movable printing device, of a manipulating member therefor, a reciprocating bed plate having a tag engaging shoulder and connections with the manipulating member for actuation thereby in timed relation to the movements of the printing device, a reservoir in overriding operative 100 relation to the bed plate to deliver tags to the bed plate to be engaged one at a time by the shoulder of the bed plate for projection from the reservoir, and spring fingers carried by the reservoir, certain of the fingers 105 being in engaging relation to tags other than the one engaged by the shoulder of the bed plate, and others of the spring fingers projecting from the reservoir in a direction to bear upon that face of the projected tag to 110 be printed.

11. In a tag addressing machine, a movable printing device, a manipulating means therefor, a reservoir for tags, a reciprocating bed plate mounted to move across the reservoir at the bottom thereof and provided with connections to the manipulating means for actuation thereby, spring fingers on the reservoir each having a return portion in position to engage the next upper tag above 115 the one resting on the bed plate and also having an extension to engage a projected tag after being removed from the reservoir, and other spring fingers carried by the reservoir and projecting in the direction of travel 120 of the bed plate to remove a tag from the reservoir.

12. In a tag addressing machine, a reser-

voir for tags, a reciprocable bed plate forming the tag retaining bottom of the reservoir, a rockable manipulating member, a printing means carried by the manipulating member and movable toward and from the path of movement of the bed plate, and tag holding fingers carried by the reservoir and having portions extending from the reservoir into position to be engaged by the printing device and to in turn engage and hold the tag while being printed.

13. In a tag addressing machine, a reservoir for tags, a reciprocable bed plate forming the tag supporting bottom of the reservoir and movable to project tags one at a time therefrom, a printing device movable into and out of engagement with the projected tags, and tag engaging members carried by the reservoir in position to arrest movement of the tags from the reservoir, the return of projected tags to the reservoir, and for holding tags while being printed.

14. In a tag addressing machine, a printing device, manipulating means therefor, and a reciprocable bed plate having a filler constituting a platen for the printing device and comprising a section of a size to hold a tag, said filler being insertible into and secured to the bed plate and the latter being provided with connections to the manipulating means for actuation thereby.

15. In a tag addressing machine, a printing device, manipulating means therefor, and a reciprocable bed plate provided with connections to the manipulating means for actuation thereby, said bed plate having a cut away portion and a filler plate for said cut away portion of a size to receive and hold a tag, said filler plate having the tag receiving surface sunk below the plane of the corresponding surface of the bed plate.

16. In a tag addressing machine, a printing device, manipulating means therefor, a reciprocable bed plate provided with connections to the manipulating means for actuation thereby, said bed plate having a cut away portion and a filler plate for said cut away portion of a size to receive and hold a tag, said filler plate having the tag receiving surface sunk below the plane of the corresponding surface of the bed plate and having portions of its surface formed of friction material adapted to engage a tag.

17. In a tag addressing machine, a printing device, manipulating means therefor, and a movable bed plate provided with connections to the manipulating means for actuation thereby and having a cut away portion and a filler plate therefor of a size to receive a tag and having the tag receiving surface sunk below the level of the remainder of the surface of the bed plate to form a tag engaging shoulder.

18. In a tag addressing machine, a printing device, manipulating means therefor, a bed plate provided with connections to the manipulating means for actuation thereby and having a cut away portion and a filler plate therefor of a size to receive a tag and having the tag receiving surface sunk below the level of the remainder of the surface of the bed plate to form a tag engaging shoulder, said filler plate having the end portion corresponding to the eye portion of a tag sunk to a lower level than the remainder of the filler plate to accommodate the superior thickness of the eye portion of the tag.

19. In a tag addressing machine, printing means, manipulating means therefor, a reservoir for tags, a reciprocable bed plate forming the tag supporting bottom of the reservoir and having longitudinal wear surfaces and longitudinal friction surfaces in alternation, elastic tag engaging members carried by the reservoir in position to bear upon the longitudinal wear surfaces, and connections from the bed plate to the said manipulating means for actuation of the bed plate thereby.

20. In a tag addressing machine, printing means, actuating means therefor, a reservoir for tags, a reciprocable bed plate having connections to the manipulating means for actuation thereby and also having a cut away portion, a filler plate for the cut away portion having wear surfaces and friction surfaces in alternation, said filler plate being of a size to receive a tag and having its tag receiving surface sunk below the surface of the main portion of the bed plate to form a shoulder for engaging a tag where the plates join, and tag engaging fingers carried by the reservoir in position to bear upon the wear surfaces of the filler plate.

21. In a tag addressing machine, printing mechanism, manipulating means therefor, a reservoir for tags, a reciprocable bed plate having connection to the manipulating means for actuation thereby and also having a cut away portion, a filler plate for the cut away portion having wear surfaces and friction surfaces in alternation, said filler plate being of a size to receive a tag and having its tag receiving surface sunk below the surface of the main portion of the bed plate to form a shoulder for engaging a tag where the plates join, and tag engaging fingers carried by the reservoir in position to move upon the wear surfaces of the filler plate, the bed plate adjacent to the tag engaging shoulder being formed with inclined notches in the line of engagement therewith of the tag engaging members carried by the reservoir.

22. In a machine for addressing tags, a reservoir for tags, means for ejecting tags

one at a time from the reservoir, fingers projecting from the reservoir into overriding relation to the projected tags, and a printing device comprising a supporting plate, a box slidable on to and off from the supporting plate and having an ink retaining pad, an ink receiving pan having passages for the distribution of ink to the pad, and means for holding a stencil sheet against the pad comprising a frame in surrounding inset relation to the stencil sheet

and related to the fingers projecting from the reservoir to overlie said fingers when the printing device is in printing engagement with a projected tag.

15

In testimony, that I claim the foregoing as my own, I have hereto affixed my signature in the presence of two witnesses.

GEORGE THOMAS PRITCHARD.
